CENTERING DEVICE

Oswald I. Thanem, Seattle, Wash., assignor to
Continental Can Company, Inc., New York,
N. Y., a corporation of New York

Application February 27, 1946, Serial No. 650,686

6 Claims. (Cl. 153—32)

1

This invention relates to an improved guide means for directing articles traveling in single file to a movably mounted receiving member; and more particularly to an improved centering device for directing flattened can bodies fed from the bottom of a hopper to a floating mandrel on a reforming machine of the character disclosed in the Dodge et al. Patent No. 1,966,380, issued July 10, 1934.

In the manufacture of metal containers such as cylindrical metal cans which are to be shipped a considerable distance before being filled with a product, it is a trade practice in the can making industry to form the can bodies on a conventional body-making machine, and to then flatten them before shipment in order to effect the greatest economy of shipping space and the resultant low cost of delivery to the packer.

When the flattened cans have been received by the packer, they are reformed into their original cylindrical shape by a reforming machine of the character disclosed in the U. S. Patent No. 1,966,380 to Dodge et al., issued July 10, 1934, after which the bottom ends are attached to the can bodies by the customary double seaming operation and the cans are then ready to be filled with the product.

In carrying out the reformation of the can bodies, the flattened bodies are fed one at a time from the bottom of a hopper by a mechanism analogous to that disclosed in the application for patent on Feeder for flattened can bodies, filed December 29, 1945, by William Furminger, S. N. 637,885.

The reforming machine receives the flattened can bodies on a horn which floats on a support. This horn receives the body from a conveyor. However, as the horn is a floating one, it is not always in the plane of the conveyor. It is, therefore, necessary to guide the individual articles such as can bodies and center them on the point of the horn. For this purpose it has been customary to provide separate upper and lower shoes. However, they are subject to excessive wear and do not insure against jams caused by can bodies being fed over or under the horn.

A primary object of the present invention is to provide an improved device of the character hereinafter described for positively guiding flattened can bodies onto a floating reforming mandrel of a can body reforming machine.

My improved mechanism provides a unitary device for centering the flattened bodies in line for being fed to the horn.

Another object of my invention is to provide an

adjustment of universal type in which there is a pivotal adjustment vertically leading the can bodies to the level of the horn. A further object of my invention is to adjust the feeding operation so that the can body is given a definite pivotal movement horizontally, inwardly and toward the longitudinal axis of the horn.

Other incidental objects of my invention will be apparent from the following description of the preferred form of my invention as illustrated in the accompanying drawings in which:

Fig. 1 is a side elevation of my improved centering device;

Fig. 2 is a plan view,

Fig. 3 is an end view of the same and

Fig. 4 is a vertical section on the line 4—4 of Fig. 1.

For the purpose of illustration I have shown the base 6 of a feeding machine for flattened or collapsed can bodies such as is more fully disclosed in the above identified patent application of William Furminger.

This feeding machine has a pair of super-imposed guides 7 and 8 between which the flattened can body 9 or similar article is advanced by a chain conveyor, the opposite edge of the body 9 resting on a guide ledge 8 which with guide 8 forms a track.

On the side of the base 6 there is a bracket 10 upon which the centering device is mounted. The front face of the bracket 10 has a horizontal channel 11 which accommodates the centering shoe. The outer end of the bracket has a horizontally extending arm 12 by means of which spring tension may be applied to the centering shoe proper.

I have shown at 13 the usual pointed horn of the reforming machine. This horn has a floating support, well known in the industry. In other words, the point of the horn is subject to lateral and vertical movement in the normal course of the operation of the machine.

The centering shoe proper 14 extends horizontally in the channel 11 of the bracket and runs from the guides 7 and 8 past the point of the horn 13. The inner face of the shoe 14 has a guiding groove 15. The vertical cross section of this groove may be any form suitable to accommodate the rounded side edge of the can body 9. However, I have shown it in the preferred V-shaped cross section as I find this will guide the edge of the can body with greatest precision and minimum friction or wear.

The front end of the shoe 14 carries a horizontal rock shaft 16 which extends backward

55

through a suitable opening in the bracket 10 and is held by pin 16'. The free end of the rock shaft 16 is recessed to hold the end of a coil spring 17. This coil spring is attached at its other end to an adjusting rod 18. This adjusting rod is adjustably held in the end of the arm 12 by means of nuts 19, 19.

The rock shaft 16 is loosely journaled in a horizontal bearing 20 provided in the opening of the bracket 10. By virtue of this arrangement the front end of the shoe 14 is held at a fixed elevation in the plane of the can body on the conveyor and the rear end of the shoe 14 is free to receive the point of the horn 13 regardless of the vertical or horizontal shift in the latter's position. This point as illustrated in the drawings is received in the V-shaped groove of the shoe.

The journal bearing 20 is held by a pair of vertical pivot pins 21, 22 adjustably threaded in the bracket 10. These pins are held in adjusted positions by means of the nuts 23. The shoe 14 is thus given a freedom for horizontal movement around the pins 21, 22 as the pivot. This, together with the tension from the coil spring 17, insures the rear end of the shoe 14 fitting around the point of the horn 13. The rear end of the shoe will, of course, be deflected away from the horn in order to permit the latter to receive a flattened can body.

By reason of the universal freedom of movement given the front end of the shoe 14 by its horizontal pivoting on the pins 21, 22 and vertically in the journal bearing 20, the rear end of the shoe will follow the movement of the point of the horn and at all times serve to guide the flattened can body. As the can body approaches the horn, it will be brought into whatever vertical plane the latter occupies and will be urged horizontally toward the point of the horn.

This form of centering device or shoe is an effective means for transferring the can bodies from a horizontal chain conveying means to the reforming horn or like device. It operates with a minimum of friction or wear due to its universal adjustment. It is simple, durable and effective.

While the preferred form has been shown and described for the purpose of example, it is believed that the invention is subject to embodiment in various forms and proportions limited solely by the scope of the following claims.

What I claim is:

1. A device for guiding flattened can bodies and the like along a track to a floating forming mandrel, comprising a support, a bearing held by the support for pivotal movement horizontally, a shoe journaled at one end in the bearing for pivoted movement vertically, said shoe having a guiding channel opposite one side of said track, and in line with said mandrel, and tension means for swinging the free end of the shoe laterally.

2. A device for guiding flattened can bodies and the like along a track to a floating forming mandrel comprising a support, vertically aligned pivots on the support, a journal bearing held by the pivots, a rock shaft passing through the bearing, a shoe attached by one end to the shaft, said shoe having a guiding channel opposite one side of said track and tension means from the free end of the shaft to the support urging the latter into engagement with the mandrel.

3. A device for guiding flattened can bodies and the like along a track to a floating forming mandrel comprising a bracket, vertically aligned pivots on the bracket, a journal bearing held by the pivots, a rock shaft extending through the bearing, a shoe attached by one end to the shaft, said shoe having a guiding channel opposite one side of said track and a coil spring anchored under tension between the free end of the shaft and the bracket urging the latter into engagement with the mandrel.

4. A device for guiding flattened can bodies and the like along a track to a floating forming mandrel comprising a bracket having a laterally extending arm, vertically aligned pivots on the bracket, a journal bearing held by the pivots, a rock shaft extending transversely through the bearing and bracket, a shoe attached by one end to the shaft, said shoe having a guiding channel opposite one side of said track and a coil spring anchored under tension between the free end of the shaft and the arm of the bracket urging the latter into engagement with the mandrel.

5. In combination, a floating horn for reforming flattened can bodies, a track for feeding flattened can bodies, a device for guiding the bodies to the horn, said device comprising a support, a bearing held by the support for pivotal movement horizontally, a shoe journaled at one end in the bearing for pivotal movement vertically, tension means for swinging the free end of the shoe laterally toward the horn, and said shoe having a longitudinal guiding channel to fit over the point of the reforming horn.

6. A device for directing flattened can bodies along a track to a can body reforming machine having a floating mandrel, comprising a guide bar having a groove extending longitudinally in a side thereof, a universal mounting for supporting an end of the guide bar adjacent the path of can body travel, said mandrel being receivable in the groove of the guide bar at the opposite end thereof, and spring means operatively connected with the guide bar for retaining the groove thereof in yielding engagement with the mandrel and thereby directing onto the mandrel can bodies conveyed through the groove.
